CAN OPENER AND SPOUT

Joseph F. Moran, Waterbury, Conn., assignor to
 Scovill Manufacturing Company, Waterbury,
 Conn., a corporation of Connecticut

Application February 15, 1934, Serial No. 711,306

9 Claims. (Cl. 221—23)

This invention relates to can spouts adapted to be punched through the top of a metal can containing a liquid, and more particularly to a can spout of the above nature having interlocking and non-leaking engagement with the top of the can.

One object of this invention is to provide a can spout of the above nature having a pair of curved cutter blades which are adapted to cut a pair of opposed semi-circular adjacent openings in the top surface of the can, leaving a cross-rib or bridge interposed between said openings.

A further object is to provide a can opener 15 spout of the above nature in which there is provided a pair of inwardly extending spaced alined wings on the interior of the spout member which are adapted to force the two sections of metal cut out by the cutters downwardly into 20 a vertical position so as not to obstruct the flow of the liquid from said can.

A further object is to provide a can spout of the above nature with a removable cap which covers the pouring end of the spout when the 25 spout is assembled to a can, and the liquid is not being poured, and which cap also serves to protect the sharp cutters of the spout when the spout is not in use.

A further object is to provide a device of the 30 above nature which will be simple in construction, inexpensive to manufacture, easy to install and manipulate, compact, ornamental in appearance, and very efficient and durable in use.

With these and other objects in view there 35 has been illustrated on the accompanying drawing, one form in which the invention may be conveniently embodied in practice.

In the drawing:

Fig. 1 represents a perspective view of a can 40 opener spout as it appears when placed on the top of a can, prior to the piercing operation.

Fig. 2 is an elevation of the same, partly in section, as it appears in fully assembled position on the can top.

Fig. 3 is a fragmentary sectional view, taken 45 on the line 3—3 of Fig. 2, of the cutting end of the spout when turned 90 degrees from the section of Fig. 2.

Fig. 4 is a fragmentary view in elevation of 50 the cutting end of the spout, showing the removable cap fitted over the cutting knives, said cap being shown in section.

Fig. 5 is an end view of the cutting end of the can spout.

Fig. 6 is a fragmentary perspective view of a

tin can as it appears when the spout has been removed, and showing the two semi-circular holes pierced therein by the insertion of said spout.

Referring now to the drawing in which like reference numerals denote corresponding parts throughout the several views, the numeral 10 indicates a tubular body or spout preferably cylindrical, and having the major portion of its outer surface roughened by means of longitudinal ribs 11 to provide a secure hand-gripping surface thereon. The lower end of the tubular spout is provided with a pair of opposed integral projecting cutting knives 12, 12, each of said knives 12, 12 having a longitudinal vertical 15 straight edge 13 parallel with the spout axis, and a helical cutting edge 14 inclined at a sharp angle to said straight edge for producing a sharp point 15. By means of this construction, when the device is forcibly inserted in the top 16 of a 20 can 17, a pair of semi-circular lug portions 18 are cut out from the metal thereof, leaving apertures 19 separated by a bridging member 20 therebetween.

In order to force the lugs 18 out of the apertures 19 during the can piercing operation, provision is made of a curved band 21 having a pair of inwardly extending alined spaced cam lugs 21a, 21a, as best shown in Fig. 3. The lower adjacent corners of the lugs 21a, 21a are formed 30 with rounded edges 22, 22, which, when the spout is being inserted within the cam top, are adapted to bear against the two lug portions 18, and forcibly bend them downwardly into a vertical position, thus leaving the apertures 19 unobstructed.

To lock the can spout upon the can top in a hermetically sealed condition, the base sections of the cutter knives 12 are provided with a pair of oppositely extending transverse slots 23, 23, 40 which extend inwardly from the upper ends of the vertical edges 13 of said knives 12, and which are adapted when the spout is partially rotated, to embrace the unsevered connecting necks 24, 45 24 at the ends of the bridging member 20.

For preventing leakage during pouring from the can spout, a horizontal annular flange 25 is secured to the exterior of the spout adjacent the upper ends of the knives 12, 12. The flange 25 50 has an integral neck band 26 which is adapted to be soldered to the outer surface of said spout. A suitable packing washer 27 is positioned underneath the annular flange 25, and is adapted to be compressed between said flange 25 and the 55

top surface 16 of the can 17 to form a tight seal therebetween.

When the spout 10 has been inserted in the can top, but is not being used for pouring purposes, the open end of said spout may be sealed by means of a cylindrical slip cap or cover 28, which is detachably fitted over the pouring end of said spout 10, as shown in Figs. 1 and 2. When the spout 10 is detached from the can, the cover 28 may be reversed and slipped over the cutting knives 12, 12 of the spout 10, as shown in Fig. 4 to serve as a protective guard for the same. The cover cap has a domed head 29 adapted to fit the hand of the user when forcing the spout into the can top, and protect it from being cut by the end of the spout.

Operation

In operation, when it is desired to open a can, the cover cap 28 will first be removed from the cutting knives 12, and slipped over the opposite or pouring end of said spout. With the cover 28 thus assembled, the spout 10 may then be placed on the top of the can 17 in the position shown in Fig. 1. Force will then be applied to the spout, causing the points 15, 15 of the cutting knives 12, 12 to puncture the top surface 16 of the can. The spout will then be swung back and forth in such a manner as to cause the knives 12, 12 to cut out the pair of opposed openings 19 in the can top 16, as shown in Fig. 6. When the spout 10 has been pushed inwardly as far as it will go, as permitted by the flange 25, the spout will be twisted in a clockwise direction to firmly interlock the necks 24 of the bridge 20 in the slots 23 and hermetically seal the spout upon the top of the can 17. The can is then ready for pouring the liquid through the spout.

In order to detach the spout from the can after the desired quantity of liquid has been poured out, it is only necessary to twist the spout in a counter-clockwise direction until the slots 23, 23 are clear of the necks 24, 24 of the bridge member 20, and then pull straight out on the spout 10.

While there has been disclosed in this specification one form in which the invention may be embodied, it is to be understood that this form is shown for the purpose of illustration only, and that the invention is not to be limited to the specific disclosure but may be modified and embodied in various other forms without departing from its spirit. In short, the invention includes all the modifications and embodiments coming within the scope of the following claims.

Having thus fully described the invention, what is claimed as new and for which it is desired to secure Letters Patent, is:

1. In a combination can opener and spout, a tubular spout member having a pair of depending semi-circular cutters adapted to pierce a pair of curved wings from the flat top of a can leaving a narrow bridge between said wings, means located between said cutters for forcing said wings downwardly, exterior packing means adapted to engage the top of said can located adjacent said knives and surrounding said spout, said bridge having interlocking engagement with said spout member to hold it in rigid detachable position on said can.

2. In a combination can opener and spout, a tubular spout member having a pair of depending semi-circular cutters adapted to pierce a pair of curved wings from the flat top of a can

leaving a narrow bridge between said wings, a pair of radial lugs located between said cutters for forcing said wings downwardly, exterior packing means adapted to engage the top of said can located adjacent said knives and surrounding said spout, said bridge having interlocking engagement with said spout member to hold it in rigid detachable position on said can.

3. In a combination can opener and spout, a tubular spout member having a pair of depending semi-circular cutters adapted to pierce a pair of curved wings from the flat top of a can leaving a narrow bridge between said wings, means located between said cutters for forcing said wings downwardly, said bridge having interlocking engagement with said spout member to hold it in rigid detachable position on said can.

4. In a combination can opener and spout, a tubular spout member having a pair of depending semi-circular cutters adapted to pierce a pair of curved wings from the flat top of a can leaving a narrow bridge between said wings, means located between said cutters for forcing said wings downwardly, exterior packing means adapted to engage the top of said can located adjacent said knives and surrounding said spout, the base of said cutters having slots to fit under said bridge member when said spout is rotated after being inserted to its full depth in said can top.

5. In a combination can opener and spout, a tubular spout member having a pair of depending semi-circular cutters adapted to pierce a pair of curved wings from the flat top of a can leaving a narrow bridge between said wings, a pair of aligned radial lugs located between said cutters for forcing said wings downwardly, exterior packing means adapted to engage the top of said can located adjacent said knives and surrounding said spout, said bridge having interlocking engagement with said spout member to hold it in rigid detachable position on said can.

6. In a combination can opener and spout, a tubular spout member, a pair of opposed cutting arcuate knives formed integral with one end of said member, each of said knives having a straight longitudinal edge and a helical edge converging to form a sharp point, whereby when said knives are forced downwardly into a can top, a pair of opposed semi-circular wings will be cut therefrom leaving a narrow intermediate bridge therebetween, an annular flange plate surrounding said spout above the roots of said cutting knives, a packing washer positioned under said flange, said cutting knives having a pair of transverse slots cut inwardly from the upper ends of said straight edges and adapted to have interlocking engagement with the under part of said bridge when the device is rotated after said cutters have been inserted to their full depth in said can top, the relative position of said slots and said flange being such that said washer will be tightly compressed between the can top and the annular flange of said spout when in assembled position.

7. In a combination can opener and spout, a tubular spout member, a pair of opposed cutting arcuate knives formed integral with one end of said member, each of said knives having a straight longitudinal edge and a helical edge converging to form a sharp point, whereby when said knives are forced downwardly into a can top, a pair of opposed semi-circular wings will be cut therefrom leaving a narrow intermediate bridge therebetween, an annular flange plate

surrounding said spout above the roots of said cutting knives, a packing washer positioned under said flange, said cutting knives having a pair of transverse slots cut inwardly from the upper ends of said straight edges and adapted to have interlocking engagement with the under part of said bridge when the device is rotated after said cutters have been inserted to their full depth in said can top, the relative position of said slots and said flange being such that said washer will be tightly compressed between the can top and the annular flange of said spout when in assembled position.

8. In a combination can opener and spout, a tubular spout member having a pair of depending semi-circular cutters adapted to pierce a pair of curved wings from the flat top of a can leaving a narrow bridge between said wings, a pair of radial lugs having curved bottom edges for engagement with said wings located between said cutters for forcing said wings downwardly, exterior packing means adapted to engage the top of said can located adjacent said knives and

surrounding said spout, said bridge having interlocking engagement with said spout member to hold it in rigid detachable position on said can.

9. In a combination can opener and spout, a tubular spout member, a pair of opposed arcuate cutter knives at one end of said member, each of said knives having a straight longitudinal edge and a curved edge converging to form a sharp point, whereby when said knives are forced downwardly into a can top a pair of opposed semi-circular wings will be cut therefrom leaving a narrow intermediate bridge therebetween, an annular flange plate surrounding said spout member above the roots of said cutter knives, said cutter knives having a pair of transverse slots extending inwardly from the upper ends of said straight edges and adapted to have interlocking engagement with the under part of said bridge when the device is rotated after said cutters have been inserted to their full depth in said can top.
